UNITED STATES PATENT OFFICE.

JOHN J. RIDGWAY, OF ROSEBANK, NEW YORK.

AUTOMATIC TRIPPER FOR CONVEYER-BELTS.

SPECIFICATION forming part of Letters Patent No. 760,702, dated May 24, 1904.

Application filed July 16, 1903. Serial No. 165,816. (No model.)

To all whom it may concern:

Be it known that I, JOHN J. RIDGWAY, a citizen of the United States, residing at Rosebank, Staten Island, in the county of Richmond and State of New York, have invented certain new and useful Improvements in Automatic Tripplers for Conveyer-Belts, of which the following is a specification.

This invention relates to improvements in automatic trippers for conveyer-belts of the kind wherein grain or other material is conveyed from one place to another.

The object of the invention is to provide automatic tripping means for controlling the propelling mechanism of the deliverer, so that said deliverer upon reaching the extreme of its travel will have its propelling mechanism automatically reversed and will travel to its other extreme, when the propelling mechanism will again be reversed, such operation being continuous as long as may be desired.

Another object of the invention is to construct and distribute the mechanism designed to accomplish this result in such manner that the deliverer will be properly balanced and not liable to strain, overbalancing, or cumbrousness of structure, and, further, that the operation of reversing the driving mechanism will be practically instantaneous, thereby keeping the deliverer in course of constant travel as long as the conveyer-belt is being operated.

I am aware that deliverers for conveyer-belts of this kind are not wholly new; that means for automatically reversing the deliverer when the deliverer is operated by the conveyer-belt have been previously employed; but such former constructions have been quite undesirable and unsatisfactory by reason of having all the clutching, tripping, and reversing mechanism located on one side of said deliverer, thereby rendering it more or less uncertain in its travel. Thus unequal distribution of weight places too much strain on one side of the deliverer and oftentimes causes it to become inoperative. In the present invention these difficulties are obviated and a mechanism constructed and arranged wherein the clutches controlling the direction the deliver-

er will travel are located on one side of the framework of the deliverer, while the tripping and reversing means controlling the clutches are located on the opposite side of said deliverer. The advantages obtained by this constructive relation of parts and the construction of the same will be hereinafter more fully explained and then pointed out in the annexed claims.

In the accompanying drawings, Figure 1 is a side elevation of a conveyer-belt and deliverer, certain parts being broken away and omitted, as they form no part of the present invention. Fig. 2 is a vertical transverse section on the line A—A with certain parts omitted to more clearly show the operative relation of the clutches.

In the practical application and construction of the invention, 1 are the supporting frames, suitably bound together to form a traveling carriage for the operating mechanism.

2 is a hood, and 3 a chute attached thereto for conveying the grain or other material to the bins or chutes below. A conveyer-belt 4, supported in a pulley, (not shown,) passes over an idler-pulley 5, thence around an idler 6, and finally passes along the bottom of the deliverer to a suitable driving-pulley, preferably located on the right side of the machine. (Not shown.) Suitably journaled in the supporting-frames 1 is a shaft 8, on one end of which is mounted a large gear-wheel 9, and on the other end is attached a pinion 10, meshing with and driving a gear 11, forming part of one of a pair of track-wheels 12, said track-wheels being adapted to travel on the track 13. The tubular shafts 15 and 16, upon which the idlers 5 and 6 are respectively mounted, are suitably journaled in the supporting-frames 1 and have loosely mounted on one end thereof driving-pinions 17 and 18, which are held in constant mesh with the large gear 9. By arranging the conveyer-belt in the manner shown in the drawings it will be observed that the idlers 5 and 6 are driven in opposite directions, as shown by arrows in Fig. 1. This is essential in order to give the large gear 9 a reverse movement when the clutch mechanisms forming part of the shafts 15 and

16 are operated to place the pinions in operative engagement with said gear.

The driving-pinion 17 is placed in operative relation with the large gear 9 by means 5 of the following clutch mechanism. The pinion is loosely mounted on the idler-shaft 15 and is held in constant mesh with the large gear 9 by means of a collar 20, secured on the end of the idler-shaft, and a clutch-collar 21, 10 loosely mounted on said shaft, said clutch-collar being movable into frictional engagement with the face of the pinions by a U-shaped wedge-block 22. The tubular shaft 15 has transverse slots cut therein through 15 which the wedge-block projects, the ends of said block being adapted to engage the clutch-collar for the purpose above described.

Extending longitudinally through the tubular shaft 15 and capable of longitudinal and 20 rotative movement is a thrust-bar 25, one end of which is adapted to engage the wedge-block 22 and force said wedge-block into engagement with the clutch-collar 21. The opposite end of the thrust-bar is screw-threaded, 25 as shown at 26, and engages a similarly-threaded bracket-plate 27, secured to the side frame 1 in any desirable manner. The screw-threads on the thrust-bar are of a very coarse pitch, so that very slight rotation of said bar 30 will force the wedge-block against the clutch-collar. The idler-shaft 16 is also provided with a collar 20' for holding the pinion 18 in mesh with gear 9, and a clutch-collar 21' engages a wedge-block 22', said wedge-block being 35 operated by the thrust-bar 25', which, like the thrust-bar 25, has screw-threads 26' cut thereon, engaging a bracket 27', but are of an opposite pitch for moving it into engagement with the wedge-block. Splined on the outer 40 ends of the thrust-bars 25 25' are sprocket-wheels 28 and 29, which receive and are operated by a belt or sprocket-chain 30, said chain passing around the sprocket and also around an oscillating segmental sprocket-wheel 31, suitably 45 journaled on a stud 32, supported in the side frame 1. Rigidly secured on the stud 32 outside of the segmental sprocket is a reversing or tripping lever 35, the upper end of which carries a weight 36 for positively and quickly 50 moving said lever after it has passed the vertical position. The segmental sprocket-wheel has an upwardly-projecting plate 33, which is provided with a concentric slot 37, in which rides a pin 38, attached to the reversing-lever. 55 Secured in the slots by suitable screws are adjustable blocks 40, by means of which the relative movement of the reversing-lever and segmental sprockets can be determined. Attached to the rail or track and projected in 60 the path of the reversing-lever are stops 41 for operatively engaging said lever, one of which is shown in Fig. 1.

When the parts are in the position shown in Fig. 1, the deliverer is traveling toward

the right, the segmental sprocket having been 65 moved by the reversing or tripping lever so that the sprocket-chain has operated the sprocket 28 and driven the thrust-bar 25 against the wedge-block 22, causing said block to force the clutch-collar into frictional engagement with the pinion 17, thereby locking said pinion with the idler-shaft 15 and turning the large gear in the direction indicated by arrow. Simultaneously with the inward movement of the thrust-bar 25 is the outward 70 movement of the thrust-bar 25', thereby instantly releasing the pinion 18 when the pinion 17 is brought into operative relation with gear 9. This result is accomplished by having the screw-threads on the ends of the 80 thrust-bars at a relatively opposite pitch or right and left threads, so that when the segmental sprocket is operated the thrust-bars will, through the medium of the sprocket-chain and sprocket-wheels, be moved in opposite directions. When the lower end of the reversing-lever strikes the stop 41, it will move said reversing-lever gradually until passing the vertical position, whereupon the weight 36 will carry it rapidly to the right, 85 causing the pin 38 to strike the adjustable stop 40 and rock the segmental sprocket from right to left, moving the sprocket-chain therewith, causing thrust-rod 25 to be withdrawn from contact with the wedge-block 22, releasing the clutch-collar, and freeing pinion 17 from operative relation with gear 9. At the same time the thrust-rod 25 will be moved into contact with wedge-block 25', causing clutch-collar 21' to engage pinion 18, and place 90 said gear in operative relation with gear 9. 95

While I have shown the device as being worked automatically, of course it is obvious that the reversing-lever can be manually operated to produce the same results.

Having thus described my invention, the following is what I claim as new therein and desire to secure by Letters Patent:

1. The combination in a deliverer for conveyers, of a conveyer-belt, idler-pulleys and their supporting-shafts driven by said belt, driving-wheels for giving travel to the deliverer, driving means normally free on the idler-shafts and connected with said driving-wheels, clutching means for holding the driving 110 means in operative relation with the idler-shafts, a tripping device, and means controlled by the tripping device for causing the clutching means to alternately place the driving means in operative relation with the driving-wheels.

2. The combination in a deliverer for conveyers, of a conveyer-belt, idler-pulleys driven thereby, hollow shafts for supporting said pulleys, driving-wheels for giving travel to the deliverer, driving means for operating the driving-wheels loosely carried on the idler-shafts, clutch devices for rocking the driving 125

means on the idler-shafts, means within the idler-shafts for operating the clutch devices, a tripping means and means controlled by the tripping means for moving the clutch-controlling means to alternately render operative and inoperative through the clutch devices, the driving means.

3. The combination of a deliverer for conveyers, of a conveyer-belt, idler-pulleys driven thereby, hollow shafts for supporting said pulleys, driving-wheels for giving travel to the deliverer, driving means for operating the driving-wheels loosely mounted on the idler-shafts, clutch devices for locking the driving means on the idler-shafts, thrust-bars alternately movable within the idler-shafts to operatively control the clutch devices, tripping means and connections between the tripping means and the thrust-bars for alternately moving said bars when the tripping means is operated.

4. The combination in a deliverer for conveyers, of a conveyer-belt, idler-pulleys driven thereby, hollow shafts supporting said pulleys, driving-wheels for giving travel to the deliverer, driving means for operating the driving-wheels loosely mounted on the idler-shafts, clutch devices for locking the driving means on the idler-shafts, thrust-bars operatively controlling the clutch devices, means on said thrust-bars capable of moving them rotatively and longitudinally within the idler-shafts, tripping means and means controlled by the tripping means to engage the means for operating the thrust-bars.

5. In combination with a deliverer for conveyer-belts, of a tripping and reversing mechanism comprising a conveyer-belt, idler-pulleys and their supporting hollow shafts driven by said belt, driving-wheels for giving travel to the deliverer, and driving means connected with said driving-wheels and driven by the idler-shafts located on one side of the conveyer, clutch mechanism for alternately rendering operative and inoperative the driving

means, and tripping means for controlling the clutch mechanism located on the opposite side of the conveyer to the driving means.

6. In a reversing mechanism for conveyer-deliverers, the combination of driving-wheels for giving travel to the deliverer, driving means for operating the driving-wheels, clutch devices controlling the driving means, a plurality of hollow driving-shafts, thrust-bars within the driving-shafts for operating the clutch devices, tripping means and means operatively controlling the clutch-operating means and operated by the tripping means for simultaneously moving the thrust-bars into and out of operative engagement with the clutches.

7. In a reversing mechanism for conveyer-deliverers, the combination of a plurality of hollow shafts, driving-pinions loosely mounted thereon, clutch devices for locking the pinions on the shafts, thrust-bars longitudinally and rotatively movable within the hollow shafts and adapted to operate the clutch devices, each of said thrust-bars having cut on one end a screw-thread opposite in pitch to the other, means for rotating the thrust-bars, tripping means, and means connecting the thrust-bar-rotating means and the tripping means for simultaneously moving the thrust-bars in opposite directions.

8. A clutch mechanism for conveyers comprising a hollow driven shaft, a pinion loosely mounted thereon, friction-disks supported on the shaft in engagement with the face of the pinions, a wedge-block projecting transversely through the shaft and adapted to engage the friction-disk, a thrust-bar capable of longitudinal movement and located within the shaft and adapted to engage the wedge-block, and means for operating the thrust-bar for the purpose explained.
